UNITED STATES PATENT OFFICE.

GEORGE COLEMAN, OF LYNN, MASSACHUSETTS, ASSIGNEE, BY MESNE ASSIGNMENTS,
TO THOMAS C. ROWEN, OF SWAMPSCOTT, MASSACHUSETTS.

CHANNEL-LIP-TURNING MACHINE.

Application filed March 18, 1920. Serial No. 366,760.

To all whom it may concern:

Be it known that I, GEORGE COLEMAN, a citizen of the United States, and resident of Lynn, in the county of Essex and State of 5 Massachusetts, have invented a new and useful Improvement in Channel-Lip-Turning Machines, of which the following is a specification.

This invention relates more particularly 10 to machines for turning back the lips of previously channelled, stiffened soles, and it has for its chief object to improve upon machines of the above-designed character.

In a copending application by Andrew R. 15 Ridderstrom, filed Feb. 26, 1920, Serial No. 361,532, assigned to the same assignee as the present application, there is disclosed a channel-lip-turning machine that is provided with two feed wheels, arranged in 20 side-by-side relation, one of the feed wheels being yieldingly mounted relatively to the other, so that it may yield when pressure is brought to bear upon its periphery by the shank stiffener of a shank-stiffened sole.

25 A feature of the present invention contemplates the provision, in a machine of the above-described character, of two feed-wheel sections one of which is constituted of yielding material, so that the feed-wheel 30 sections may be rigidly secured together, whereby the construction is simplified and the cost of manufacture reduced. A further feature resides in a novel feed mechanism.

With the above and other objects in view, 35 the invention consists of the improved machine hereinafter described, illustrated in the accompanying drawings and defined in the appended claims.

In the drawings, illustrating a preferred 40 embodiment of the present invention, Fig. 1 is a side elevation, partly in section of so much of a machine embodying the present invention as is necessary to an understanding thereof; Fig. 2 is a sectional view taken 45 upon the line 2—2 of Fig. 1, looking in the direction of the arrows, showing the act of turning over and pressing down the lip of a channelled sole; and Fig. 3 is a front elevation of parts of the machine shown in 50 Fig. 1.

The machine of the present invention is provided with a horizontally rotatable wiper 2 that is adapted to open, turn over and press flat a channel lip 4 of a previously 55 channelled sole 6. As the lip 4 is subjected

to considerable strain by the wiper, the sole must be firmly gripped to prevent its being pushed bodily out of and away from the machine. The desired firm gripping action is effected by a powerfully spring-pressed 60 toothed feed wheel 8 that bites deeply into the leather on one face of the sole, and by the wiper 2 and a presser foot 10 acting upon the other face of the sole. As the sole is advanced by the feed wheel to the wiper, 65 it is guided by an adjustable guide 12 that lies in the sole channel and bears against the shoulder of the lip, and it is gauged by an adjustable gauge 14. The action of the above-described instrumentalities is well 70 understood by persons skilled in the art and a fuller description thereof may be found, for example, in a patent to Stanbon, No. 607139, granted July 12, 1898.

The machine of the said patent is ill 75 adapted to the requirements of stiffened soles, such as the molded outsole shown in the drawings, the shank of which is stiffened with the shank stiffener 16. As described in the above-mentioned application by Ridderstrom, there is a tendency, owing to the firm gripping action of the feeding instrumentalities, for the sole to wedge in between the elements of the feeding mechanism, resulting either in stopping the operation of 80 85 the machine, or in injuring the outsole or the machine parts.

According to the present invention, this tendency is overcome by mounting concentrically with the feed wheel 8, adjacent 90 thereto and in side-by-side relation therewith, a second feed wheel 22 constituted of yielding material, like rubber. The feed-wheel of the machine of the present invention is thus constituted of the two feed-wheel 95 sections 8 and 22.

The feed wheel 22 may be of varying thickness, dependent upon the dimensions of the shank of the sole, and its position upon the machine should be such that the force 100 exerted by the wiper wing in pressing back the channel lip shall lie along a line L, Fig. 1, parallel to the feed wheel 22 and midway between its faces. It therefore becomes necessary to mount the feed wheel 8 farther to the left, as viewed in Fig. 1, than is the case in the above-referred-to Stanbon patent. The feed wheels may be inclinedly mounted upon a rotatable, inclined shaft 24 and they may be rigidly secured together, 105 110

so as to rotate as a unit, by a screw 26 and a pin 28, the latter being shown as passing through an opening in the feed wheel 8 and embedded in the feed wheel 22. The 5 periphery of the feed wheel 22 may be conically inclined, so to render its uppermost portion 30 more nearly horizontal, thereby providing for a larger bearing surface and a more uniform gripping action upon the steel 10 shank 16. Better cooperation is thus furthermore secured with the inclined wiper wings. A washer 32, of diameter less than the diameter of the smaller face of the feed wheel 22, acts to prevent spreading of the 15 material of which the feed wheel 22 is constituted.

In operation, the feed wheel 22 yieldingly 20 grips the shank 16 and the feed wheel 8 firmly grips an adjacent edge portion of the sole, the other face of the sole being firmly gripped by the presser foot and the wiper. The feed wheels are rotated by power transmitted to the shaft 24. As the sole is thus advanced by the feed wheels, the channel-lip 25 is opened, turned over and pressed back by the wiper. Owing to the yielding action of the feed wheel 22, the machine can not become clogged up, but continues to operate smoothly and without injury to the sole or 30 to the machine. This result is attained, furthermore, in simple fashion and without the jostling lateral bodily movement of the yielding feed wheel which characterizes the above-mentioned Ridderstrom machine, and 35 the present machine can be manufactured much more economically. The frictional qualities of rubber, moreover, render this material superior to metal for feeding purposes.

40 The invention having been thus described, what is claimed as new is:

1. A feed mechanism having, in combination, two feed-wheel sections secured together in side-by-side relation, one of the 45 feed-wheel sections being constituted of rubber, the periphery of the rubber feed-wheel section being cone-shaped with the walls of the cone converging away from the other feed-wheel section, and means for securing the rubber feed-wheel section to the other feed-wheel section.

2. A channel-lip-turning machine having, 50 in combination, a wiper, means for feeding a shank-stiffened sole to the wiper comprising two feed-wheel sections disposed in side-by-side relation and rotatable about an axis, one of the feed-wheel sections being constituted of yielding material and adapted to

yieldingly grip the shank stiffener, and the other feed-wheel section being adapted to 60 firmly grip an adjacent portion of the sole, means co-operating with the feeding means to grip the sole, and means for operating the feeding means.

3. A channel-lip-turning machine having, 65 in combination, a rotatable wiper, means for feeding a shank-stiffened sole to the wiper comprising two feed-wheel sections inclined-disposed to the wiper in side-by-side relation and rotatable about an axis, one of the feed-wheel sections being constituted of yielding material and adapted to yieldingly grip the shank stiffener, and the other feed-wheel section being adapted to firmly grip 70 an adjacent portion of the sole, the periphery of the first-named feed-wheel section being cone-shaped with the walls of the cone converging away from the second-named feed-wheel section, means for preventing spreading of the yielding material of the first-named feed-wheel section, the feed-wheel sections being positioned so that the force exerted by the wiper shall lie 75 along a line substantially parallel to the first-named feed-wheel section and midway between its faces, means co-operating with the feeding means to grip the sole, and means for operating the feeding means.

4. A machine of the class described having, 80 in combination, operating means, and means for feeding to the operating means material to be operated upon, the feeding means comprising two feed-wheel sections disposed in side-by-side relation and rotatable about an axis, one of the feed-wheel sections being constituted of non-yielding material, and the other feed-wheel section being constituted of yielding material, the feed-wheel sections being positioned so that the force exerted by the operating means shall 85 lie along a line passing through the feed-wheel section of yielding material.

5. A channel-lip-turning machine having, 90 in combination, a wiper, a feed wheel for feeding a shank-stiffened sole to the wiper having a portion constituted of non-yielding material adapted to firmly grip a portion 95 of the sole adjacent to the shank stiffener and a portion constituted of yielding material adapted to yieldingly grip the shank stiffener, and means for operating the feed wheel.

In testimony whereof, I have hereunto 100 subscribed my name this 15th day of March, 1920.

GEORGE COLEMAN.
